LUMINOUS CANDLE

Virginia H. Sundell, Minneapolis, Minn., assignor
to Sunny-Lorraine Chandlery, Mound, Minn., a
partnership

Application February 15, 1947, Serial No. 728,849

2 Claims. (Cl. 67—22)

1

This invention relates to a candle and particularly to a candle of decorative or artistic form.

It is an object of this invention to provide a candle of translucent combustible material, such as certain kinds of wax, said candle preferably having a transverse dimension of substantially one-half its height, the same being slightly tapered and having a downwardly tapering recess in its upper end extending substantially from its edges and having a depth of approximately one-third of the transverse dimension of said candle, and a wick extending from the bottom of said recess downwardly centrally of said candle to the bottom thereof, whereby when said candle is lighted the flame from said wick will give a luminous or glowing effect to the top portion of said candle and the exterior light will illuminate the body of said candle to a certain depth.

It is another object of the invention to provide a luminous candle comprising a body of translucent colored combustible material, said body preferably being slightly tapered and having a downwardly tapering recess in its upper end extending substantially from the edges thereof and having an appreciable depth, said body having flakes of coloring matter spaced therein giving a cloudy or mottled effect, and a wick extending downwardly from the bottom of said recess centrally of said body to the bottom thereof whereby when said candle is lighted the flame of said wick will give a luminous or glowing effect to the top portion of said candle and the exterior light will penetrate said body and said flakes may be seen at some depth in said body.

It is a further object of the invention to provide a luminous candle having a body of colored translucent combustible material and of comparatively large transverse dimension and being square or rectangular in cross section, said body having a downwardly tapering recess in its top extending substantially from the edges thereof and of appreciable depth, said body having flakes of white or milky color spaced therein, and a wick extending downwardly centrally from the bottom of said recess to the bottom of said body whereby when said candle is lighted the flame in said wick will give a luminous or glowing effect to the top portion of said candle, the exterior light will penetrate said body somewhat so that said flakes may be seen at some depth in said body and the light will shine through the corners of said candle giving an illuminated or glowing effect.

2

It is still another object of the invention to provide a novel and efficient method for making such a candle as above set forth.

These and other objects and advantages of the invention will be fully set forth in the following description made in connection with the accompanying drawings in which like reference characters refer to similar parts throughout the several views and in which:

Fig. 1 is a perspective view of the candle in unlighted condition;

Fig. 2 is a perspective view of the candle lighted; and

Fig. 3 is a central vertical section through the candle taken at right angles to one side, a portion being shown in side elevation.

Referring to the drawings, a candle 10 is shown comprising a body of material which is combustible in connection with a wick. The candle is of large width compared to its height and in practice the candle shown on the drawings is made with the length of one side at the top being substantially three inches, the length of one side at the bottom being substantially two and three-quarters inches, while the height of the candle is five inches. The candle thus tapers slightly towards its lower end. The candle has a rather large recess 10a in its top which extends from substantially the edges of the candle downwardly in tapering form to the center of the candle. The depth of this recess is approximately one-third the length of one side of the candle at the top. A wick 11 extends from the bottom of said recess downwardly centrally of the candle to the bottom thereof. The material from which the candle is made is such that the body of the candle is quite translucent. The candle will be colored and various colors can be used. The coloring matter is generally distributed uniformly throughout the body of the candle. In some places where there is not an even distribution of said coloring matter, the flakes or portions 12 are formed. This gives a beautiful mottled or clouded appearance to the candle and due to the fact that the body of the candle is quite translucent, these portions 12 can be seen to quite a depth in the body of the candle.

While the method of making the candle could be varied considerably, in practice the method followed has consisted of melting a certain quantity of crude wax having a melting point of substantially 134° F. When this is melted substan-

tially four times the amount thereof by weight of a refined wax having a melting point of 135° F. to 137° F. is added and the two are melted together and the mixture raised to a temperature of substantially 212° F. The mixture is then removed from the heating means and substantially one-eighth of a teaspoonful of stearate is added for each one and one-quarter pounds of the said mixture. One drop of glycerine is added for each one and one-quarter pounds of said mixture. The dye is then added as desired and while various kinds and quantities of dye might be used, in practice it has been preferred to use about three grains of an oil soluble aniline dye diluted in about ten drops of benzol. The ingredients are stirred sufficiently to get a substantially uniform coloring, the mixture is then allowed to cool to about 185° F. and is then poured into molds. These molds preferably are slightly tapered toward the bottom and have in their bottoms a central upstanding portion shaped to form the recess above described. When the poured material has cooled and solidified, the candles are removed from the mold. The wicks of course will be suspended in the mold at the time of pouring.

When the candle is lighted the flame is disposed in the recess in the top of the candle and this results in the upper part of the candle being illuminated so that a glowing effect is given to said upper part, which glowing effect diminishes toward the bottom of the candle. This gives a very beautiful effect. The candles are made of cylindrical form and of rectangular or other polygonal form in cross section, some being square in cross section as is the one illustrated in the drawing. As above stated, the milky flakes or portions of coloring matter in the body of the candle can be seen and these are seen at a considerable depth due to the translucency of the material. Due to the translucency of the material the exterior light shines through a portion of the candle at the exterior thereof and this gives a luminous or illuminated effect. This is particularly true in a candle of polygonal form in cross section as the exterior light then shines through the corners so that the corner portions are given a luminous or glowing effect.

From the above description it will be seen that I have provided a novel, artistic and beautiful candle. The candle functions in a novel way as above described, giving beautiful effects. The candles are stocky and thus quite heavy and stable so that they will not fall over or be blown over. The flame is well down in the recess in the candle and this reduces any fire hazard. The candles are artistic and colorful, both in lighted and unlighted condition. The glowing effect when lighted is very cheerful and the candles are particularly adapted for use on a table or on a mantle of a fireplace. The candles are very economical and have a very long burning period. Such a candle as shown in the drawing will burn for approximately 125 hours. When the candle has burned as long as possible, a pot-like shell of wax remains which can be used as a flower pot, ash tray, or other similar article. The candle is preferably placed in or on some flat receptacle in use and the users are instructed to pinch off most of the burned portion of the wick after each burning period. It is well to turn the candle as it burns to assure even burning. The candle has a high degree of utility for use in centerpieces for a table or for similar pieces used for decoration on mantles or shelves. The candle

can be placed in the center in the bottom of a dish containing groups of flowers of various kinds and adds greatly to the effect. It is particularly beautiful in connection with a center-piece made of Christmas greens. For Christmas decoration the color is usually red or some shade of rose. The candles have been amply demonstrated in actual practice, found to be very successful and efficient and are being commercially made.

It will of course be understood that various changes may be made in the form, details, arrangement and proportions of the product and in the steps and sequence of steps of the method without departing from the scope of applicant's invention, which, generally stated, consists in a method and product capable of carrying out the objects above set forth, such as disclosed and defined in the appended claims.

What is claimed is:

1. A candle having a body of colored translucent combustible heavy material, said candle having a transverse dimension of substantially one-half the height thereof and having a downwardly tapering recess in its upper end extending from substantially its top edges to substantially its central vertical axis and having a depth of approximately one-third its transverse dimension, said body having spaced flakes of different colored material therein and a wick extending from the bottom of said recess centrally of said body to the bottom thereof and extending upwardly to a point substantially below the plane of the top of said candle whereby the flame on said wick will give a luminous or glowing effect to the upper portion of said candle and said flakes may be seen at some depth in said body by the exterior light.

2. A candle having a body of colored translucent combustible material, the same being substantially square in transverse cross section and having a downwardly tapering recess in its top extending substantially from the edges thereof to substantially its central vertical axis and having a depth of approximately one-third the transverse dimension of said candle, said body having flakes of white material spaced therein giving a mottled effect, and a wick extending centrally from said body from the bottom of said recess to the bottom of said body and extending upwardly to a point substantially below the plane of the top of said candle whereby the flame from said wick gives a luminous or glowing effect to the top portion of said candle, said flakes may be seen at some depth in said body by the exterior light and the exterior light shines through the corner portions of said candle giving a luminous effect.
